UNITED STATES PATENT OFFICE.

GODFREY M. S. TAIT, OF WASHINGTON, DISTRICT OF COLUMBIA.

APPARATUS FOR THE PROGRESSIVE HEATING OR COOLING OF MILK-BOTTLES AND OTHER CONTAINERS.

1,393,717.

Specification of Letters Patent.

Patented Oct. 11, 1921.

Application filed February 14, 1917. Serial No. 148,643.

To all whom it may concern:

Be it known that I, GODFREY M. S. TAIT, a citizen of the United States of America, and a resident of Washington, District of Columbia, have invented certain new and useful Apparatus for the Progressive Heating or Cooling of Milk-Bottles and other Containers, of which the following is a specification.

10 My invention relates particularly to apparatus for the progressive heating, or cooling, or both, of milk bottles, preserved fruit or vegetable containers such as cans or jars, etc., but is particularly intended for the 15 pasteurization or sterilization, and subsequent cooling, of filled milk bottles. My invention comprises a conveying apparatus, preferably formed of a number of similar units, which apparatus is of simple and compact construction and comprises a number 20 of different levels wherein the containers may be subjected to heating or cooling, or to heating followed by cooling or the reverse, together with means for lowering such 25 bottles or containers from one level to the another, without spilling of their contents. Other features of my invention will be pointed out hereinafter.

Each unit of my apparatus comprises two 30 rotary tables, suitably driven, together with a flat spiral guide over each such table, which guide is stationary; and also comprises a lowering device, commonly of the 35 nature of a helical conveyer, whereby the bottles or other containers may be lowered gently from the higher level to the lower level. The bottles or containers are delivered by suitable means through a receiving 40 opening in the upper spiral guide onto the rotary table beneath that guide and by the motion of the table are carried through the spiral channel of that guide to the central portion of the table, and thence are deposited upon the said helical lowering 45 device, and by that device are delivered, through a receiving opening on the lower spiral guide, to the lower rotating table, and by the motion of that table are carried 50 through the spiral chamber of that lower guide to a suitable discharge opening, and thence are carried away by suitable means. In the case of multi-stage apparatus embodying my invention there may be several 55 of these units, and the bottles or containers discharged from one such unit may be car-

ried over to the receiving point of another unit and thence carried through that unit and delivered to the receiving point of another such unit, and so on; it being practicable to use as many units of my apparatus as desired. In my Patent No. 1,094,380 dated April 21, 1914, I describe a process of pasteurizing milk in bottles which comprises passing the bottles, filled with heated milk, through a heat-retaining chamber, the 60 pasteurization being effected by the heat already imparted to the milk before the entry into such chamber; which chamber is of the nature of a so-called "fireless cooker". The apparatus herein described 65 is particularly adapted and intended for carrying out that process, though it may be provided with heating means, and thereby may be adapted for pasteurizing or sterilizing milk or other liquids, received cold, 70 or, at any rate, received at a temperature below the intended pasteurizing or sterilizing 75 temperature.

I will now proceed to describe my invention with reference to the accompanying 80 drawings, and will then point out the novel features in claims. In said drawings:

Figure 1 shows, more or less diagrammatically, a central vertical section of a multi-stage apparatus embodying my invention.

Fig. 2 shows a top view of one of the units of my apparatus, with receiving and delivering conveyers in coöperative relation therewith.

Fig. 3 shows a vertical section of such unit at a plane at right angles to the plane of section of Fig. 1, and also shows means for the separate drive of the several sections of which each table may be composed.

Referring first to Fig. 1: A and B, A' and B', A'' and B'', and A''' and B''', each designate sections of my apparatus, each two sections A and B, A' and B', etc., together constituting (together with the coöperating 100 lowering device hereinafter mentioned) a "unit" of my apparatus. Each section, A or B, etc., comprises a table, itself preferably composed of a plurality of annular rings 1 and 2 (in the construction shown each table 105 consists of two such rings only, but obviously the number of the rings may be multiplied indefinitely), which rings are separately driven, but at related speeds, as hereinafter pointed out. Above each such table 110

there is a stationary spiral guide, 3, forming above the table, a passage 4, consisting of a plurality of helical turns, leading from a receiving orifice 5 to a central chamber 6; 5 which chambers 4 and 6 are closed at the top by a top plate 7 attached to the outer wall or shell 8 of the section.

9 designates a lowering device, of the nature of a helical conveyer, located within a 10 vertical passage 10, at the center of the chamber 6, and leading to the similar chamber 6' of section B; which section B is provided with a similar spiral guide 3 forming a number of spiral turns 4 leading to a 15 discharge opening 11. This conveyer is provided with vertical projections 9' which insure that the bottles shall be engaged and carried downward by the conveyer 9, and also prevent the bottles from being upset 20 upon engagement with such conveyer or while traveling down on the conveyer.

Each annular ring, 1 and 2, of the table, is provided near its periphery, with a down-turned flange 12, provided at its bottom with 25 gear teeth. A driving shaft, 13, is provided with pinions engaging these gear-toothed flanges of the table; from which it follows that each inner annulus will be driven at a higher angular speed than the corresponding 30 outer annulus, but at the same peripheral speed as the outer annulus.

The reason for forming these tables of a plurality of annular rings driven at different angular speeds is as follows: The bottles 35 or other containers to be treated may be received by the apparatus in close succession, and if the table were formed in one section only, then owing to the progressive reduction of linear speed, as the center of the 40 table is reached, the bottles or other containers may be crowded together, near the center, to such an extent as to clog the apparatus. But by constructing the table of a plurality of annuli, driven at progressively 45 higher angular speeds, toward the center, as the bottles pass from one section of the table to another, their linear speed is increased, so preventing the clogging mentioned.

As the bottles or containers reach the central chamber 6 of the upper section A, they 50 are deposited upon the helical lowering device, 9, which carries them down to the table of the lower section B, whence they pass through the helical chamber of that section 55 B outward.

In the multi-stage apparatus shown in Fig. 1, the bottles or containers, treated in unit A—B, are carried by a suitable conveyer 15 into unit A'—B'; through which 60 unit they traverse in the same manner as unit A—B; and thence are delivered by a conveyer 16 to the unit A''—B'', and thence by means of a conveyer 17 to the unit A'''—B''', from which they are delivered by 65 a conveyer 18. There is less occasion for

using a plurality of annuli for the final table of the series, and therefore in Fig. 1 I have indicated the table 1' of the final section B''', as a unitary table. The tables of the other B sections might also be unitary, as 70 will be obvious.

The lower sections of the multi-stage apparatus will, commonly, be cooling chambers, and hence are provided with cooling coils 19 and 19'; which coils I have shown 75 connected, through valves 20 to supply and return lines 21 and 22; the reason for using two series of cooling coils being, that the same apparatus is designed to treat both quart and pint sizes of bottles; and when 80 treating quart sizes, both series of cooling coils will be used ordinarily, while when treating pint sizes only the lower cooling coils will be used ordinarily. When so desired, the upper sections of the apparatus 85 may be provided with heating coils 23 and 24 connected to supply and return lines 25 and 26 through valves 27. Of course any number of the sections of the apparatus may have cooling coils, and any number of the 90 sections of the apparatus may have heating coils; and if there ever be occasion, the coils of the upper sections may be cooling coils and those of the lower sections may be heating coils, or the coils of some intermediate 95 sections of the apparatus may be heating coils, and the upper and lower sections may have cooling coils.

In a prior application, filed May 3, 1915, Serial No. 25,555, I have claimed the helical 100 conveyer 9 provided with the projecting guides 9' which prevent the bottles from turning over as they pass to the conveyer 9 or during their transit down the conveyer 9.

What I claim is:

1. Apparatus such as described comprising a plurality of superposed rotary tables, a spiral guide above each such table adapted to receive containers and during the motion thereof on such tables to guide such containers toward or from the center as the case may be, and means for passing such containers from the one table to the other, comprising means for regulating the speed of passage of the containers from the one 110 table to the other.

2. Apparatus such as described comprising a plurality of units, one of such units being superposed above another of said units, and a third unit being disposed laterally 120 with respect to said first two units, each unit comprising a plurality of superposed tables, with spiral guides thereabove, each guide adapted to receive containers and by the motion of such containers on said tables 125 to guide such containers toward or from the center as the case may be, and comprising also means for passing the containers from the one table to the other, means for passing the containers from the discharge 130

of the upper of the two first mentioned units, to the receiving portion of the laterally disposed unit, and means for passing the containers from the discharge of the laterally disposed unit to the receiving portion of the lower of the two first mentioned units.

3. Apparatus such as described comprising a plurality of superposed tables, one of 10 which is rotary and one of which has an open center, a spiral guide above such rotary table, a helical conveyer leading from said open center and adapted to transfer containers from the one table to the other, and 15 means for carrying away the containers so transferred to the second table, said spiral conveyer comprising means for holding the conveyers upright during their transit from the one table to the other.
- 20 4. Apparatus such as described comprising a plurality of superposed tables, the upper of which is rotary and has an open center, a spiral guide above such upper table, adapted to receive containers and during 25 the motion thereof on said upper table to guide such containers toward the open center of the upper table, a helical conveyer lead-

ing from said open center and adapted to receive conveyers so carried to the open center of the upper table, and to carry such 30 containers to the lower table, and means for carrying away the containers so deposited upon the lower table, said helical conveyer comprising means for holding the containers upright during their transit from 35 the upper table to the lower table.

5. Apparatus such as described comprising a rotary table, a spiral guide, closed at the top, above such table, and adapted to receive containers and during the motion 40 thereof on such table to guide such containers toward or from the center according to the direction of rotation of the table, such spiral guide forming a heat-retaining chamber, and means within such chamber for 45 conveying a heating or cooling fluid therethrough.

In testimony whereof I have signed this specification in the presence of two subscribing witnesses.
